(57) **CLAIM**

The ornamental design for a shingle, as shown and described.

DESCRIPTION

The patent or application file contains at least one drawing executed in color. Copies of this patent with color drawing(s) will be provided by the Office upon request and payment of the necessary fee.

FIG. 1 is a top view of a shingle; and,

FIG. 2 is a top perspective view of the shingle of FIG. 1. The broken lines and the half-tone areas within the broken lines depict portions of the shingle that form no part of the claimed design. The term "SureNail" included in this unclaimed portion of the shingle is a registered trademark of Owens Corning.
